UNITED STATES PATENT OFFICE.

SIDNEY B. SEGURA, OF HOUSTON, TEXAS, ASSIGNOR TO CROWN SHOCK ABSORBER COMPANY, OF HOUSTON, TEXAS, A CORPORATION OF TEXAS.

SHOCK ABSORBER FOR AUTOMOBILES.

Continuation of application Serial No. 546,764, filed March 25, 1922. This application filed November 22, 1922. Serial No. 602,574.

To all whom it may concern:

Be it known that I, SIDNEY B. SEGURA, a citizen of the United States, residing at Houston, in the county of Harris and State 5 of Texas, have invented certain new and useful Improvements in Shock Absorbers for Automobiles, of which the following is a specification, reference being had to the accompanying drawings.

10 It is the purpose of the present invention to provide a device of this kind, by which the shocks due to the rebound movements of the automobile may be absorbed, as well as the shocks resulting from the downward 15 movements of the body.

Heretofore, the shocks resulting from the rebound movements, have been absorbed by cushions above a member of the body, and the shocks created by the body on its downward 20 movements have been absorbed by cushions below said member.

However another purpose is to reverse the order of this arrangement, that is to say, to absorb the shocks incident to the downward 25 movements of the body, by cushions disposed above an oscillatory member, and to absorb the shocks incident to the rebound movements of the body, by cushions arranged below said oscillatory member. It 30 has been found that this order of arrangement absorbs the shocks more uniformly, enabling the occupants of the vehicle to ride with greater comfort and ease than has been accomplished before.

35 A further purpose is to provide an oscillatory lever or member, one end thereof being connected to the usual leaf spring of the body, and the other end operatively mounted between upper and lower cushions 40 whereby the shocks, resulting from the downward movements of the body, are absorbed by the cushions above, and those resulting from the rebound movements of the body, are absorbed by the cushions below.

45 A still further purpose is the provision of an improved means for mounting said cushions and the oscillatory lever or member, whereby these results may be accomplished more effectively and at a relatively 50 low cost.

Also it is the aim to provide shock absorbers applicable to the forward and rear springs and axles (preferably of a Ford automobile) without making any material

alterations in the construction of the automobile.

It is to be understood that the particulars herein given are in no way limitative and that while still keeping within the scope of the invention, any desired modifications of detail and desired proportions may be made in the apparatus according to circumstances.

The invention comprises further features and combination of parts, as will be herein-after set forth, shown in the drawings and 65 claimed.

In the drawings:

Figure 1 is a rear view of an automobile showing the rear shock absorbers mounted in position, showing one of them in section; 70

Figure 2 is a view in front elevation of an automobile, showing the forward shock absorbers, there being a portion of the forward axle in section, showing how the hanger for the lower cushion is reinforced 75 relatively to the axle;

Figure 3 is a vertical sectional view on line 3—3 of Figure 1, showing the construction of the shock absorber at right angles to that shown in the preceding figures; 80

Figure 4 is an enlarged detail perspective view of the rear hanger;

Figure 5 is a detail view of the U-shaped saddle which straddles the upper and lower cushions and has the lower ends of its arms 85 operatively connected to the axle.

Figure 6 is a detail perspective view of one of the spring abutments.

Referring to the drawings, 1 and 2 designate the forward and rear axles of the automobile, and 3 and 4 denote the forward and rear springs thereof, while 5 and 6 designate the forward and rear hangers of the shock absorbers. Each hanger rises 90

from the axle, and near its lower portion 95 is provided with a lateral plate 7, which carries a cup 8. The lower portion of each hanger is provided with a U-shaped crotch 9, which straddles the axle, there being a bolt 10 passing through the extremities of 100 the arms or side walls of the crotch and engaging below the axle, to securely anchor the hanger in a perpendicular position on the axle. It is to be noted that the hanger, the plate, and the cup are all constructed in

a one-piece casting, so as to insure rigidity and strength. The outer end of the plate 105 7 of each rear hanger is connected at 11 to

the rear axle brake housing, which is adjacent the rear hub brake drum.

The construction of each forward hanger is modified, to the extent of arranging the 5 bolts 10^a adjacent the outer end of the plate 7 of the hanger, instead of at the inner end. Furthermore the inner end of each forward hanger has an extension or lug 12, which enters an opening in the forward axle, and 10 receives a nut on its lower end, which nut bears against the under face of the axle, and by this construction the forward hanger is held in place and prevented from moving inwardly.

15 The upper end of each hanger is bifurcated, and arranged between the arms 13 caused to be formed by the bifurcation 14 and fulcrumed upon a pin 15 is a lever 16. The inner end of the lever 16 is downwardly 20 turned as shown at 17 and is connected to a link 18, which in turn is fastened at 19 to a leaf spring 20 of the automobile.

The outer end of the lever 16 terminates in a head 21, which extends at right angles 25 to the lever 16, in a direction above and below the lever. The upper and lower ends of the head operatively engage sockets 22 and 23 of the reversely disposed cups 24 and 25. Arranged above the cup 24 is an additional cup 26, the upper face of which is provided with a recess 27. The cups 8, 24, 25 and 26 are spaced and are arranged in axial alignment and cooperating between the cups 8 and 25, and between the cups 24 and 26 are coil springs 28 and 29. These springs 28 and 29 are under compression, therefore the tendency of each spring is to expand.

Straddling the cups is a saddle 30, so that 40 the upper transverse portion 31 of the saddle will engage the groove or recess 27 in the upper face of the cup. In other words the transverse portion 31 of the saddle is countersunk in the cup, so that the upper 45 face of the transverse portion is flush with the upper face of the cup, there being a suitable bolt 32 passing through the transverse portion and into the cup, to secure the saddle and the cup 26 together. The 50 arms of the saddle extend downwardly on opposite sides of the various axially aligned cups 8, 24, 25 and 26, so that their lower ends will protrude below the under face of the axle. The extremities 33 of the arms of the 55 saddle receive bolts 34, which pass under the axle, thereby securely fastening the saddle in position.

The sockets 22 and 23 are of sufficient size to permit the head 21 to move freely 60 therein, so as to compensate for the oscillatory movement of the lever 16. It is well understood that when the wheels of the vehicle come in contact with a gully or depression in the roadway the body of the vehicle moves downwardly very sudden, creat-

ing shock. Therefore the shock incident to the downward movement of the body has been absorbed by cushions or springs under a member carried by the body. In the present instance, it will be noted that the 70 cushion or spring for absorbing a shock incident to the downward movement of the body is located above the lever 16, therefore, when the body moves downwardly, the lever 16 is oscillated, causing the head 21 to 75 move upwardly additionally compressing the spring 29, and allowing the spring 28 to expand. In shock absorbers heretofore produced, the shock incident to the rebound movement of the body has been absorbed 80 by means above a member carried by the body. However, in the present case the cushion or spring for absorbing the shock incident to the rebound movement of the body is located below the lever 16. It is, therefore, well understood that when the body in the present case makes its rebound movement, the head 21 of the lever 16 moves downwardly, compressing the spring 28, and allowing the spring 27 to expand, thereby absorbing the shock, as a result of the rebound movement of the body.

It will be noted that due to the links 18 the body of the vehicle is permitted to have lateral play relatively to the hangers 6, for it is clear that if it were not for the links 18, considerable lateral strain would be imparted upon the hangers 6, as a result of any movement of the body in a horizontal or lateral direction.

100 This application is filed in continuation of the application of Paul A. Leckrone and Sidney B. Segura, filed March 25, 1922, Serial No. 546,764.

The invention having been set forth, what 105 is claimed is:—

1. In a shock absorber, an axle, a hanger mounted thereon, superimposed cushions supported on said hanger, a vehicle body supporting spring, a member mounted upon the hanger for oscillatory movements having one end connected to the vehicle body supporting spring and its other end operatively engaging with and between said cushions, and means straddling the cushions and connected to the axle, thereby holding the cushions in place and slightly under compression, said means comprising a U-shaped saddle, the arms of which engage on opposite sides of the cushions and have their lower extremities extending beyond the lower face of the axle, to receive said securing means.

110 2. In a shock absorber, an axle, a hanger mounted thereon, superimposed cushions supported on said hanger, a vehicle body supporting spring, a member mounted upon the hanger for oscillatory movements having one end connected to the vehicle body supporting spring and its other end opera-

tively engaging with and between said cushions, and means straddling the cushions and connected to the axle, thereby holding the cushions in place and slightly under compression, said means comprising a U-shaped saddle, the arms of which engage on opposite sides of the cushions and have their lower extremities extending beyond the lower face of the axle, to receive said seat curing means, the upper cushion including a cup for holding the cushioning member proper of the upper cushions in place, said cup having a recess or groove for the reception of the upper transverse part of the saddle, and means for securing the transverse part of the saddle in said groove.

3. In a shock absorber, an axle having a hanger supported thereon, a pair of cushions supported upon the hanger, said cushions 20 each comprising axially aligned cups, springs operatively engaging in and between said cups, a vehicle body supporting spring, means operatively mounted upon said hanger for oscillatory movements and connected to said vehicle body supporting 25 spring, and in turn operatively and loosely connected with the outer faces of the adja-

cent cups of both cushions, and means for holding the cups in axial alignment.

4. In a motor vehicle, the combination with 30 the leaf spring and axle, of a supporting post on said axle, a hanger on said axle outside said post, a lever pivoted on said post and flexibly connected at one end to said leaf spring, a head on the outer end of said lever within 35 said hanger, cups above and below said head, and compression springs in said hanger between said cups and the opposite ends of said hanger.

5. In a motor vehicle, the combination with 40 the leaf spring and axle, of a supporting post on said axle, a lever pivoted on said post, the inner end of which is secured to said leaf spring, a hanger on said axle outside 45 said post, a head on the outer end of said lever, cups at the upper and lower ends of said hanger, bearing cups above and below said head, and coiled springs between said bearing cups and said first-named cups for the purpose described. 50

In testimony whereof I hereunto affix my signature.

SIDNEY B. SEGURA.
